PAVING CONSTRUCTION

Lytle S. Adams, New York, N. Y.

Application December 11, 1929, Serial No. 413,371
Renewed January 16, 1933

28 Claims. (Cl. 94—4)

Great difficulty is experienced, in many of our southern cities, frequently subjected during the summer months to sudden thunder storms, because of the inadequacy of the sewage systems to take care of the excessive rainfall accompanying such storms. The drainage systems frequently become filled to overflowing with the result that the streets become flooded causing injury to property and delay of traffic. A study of this problem has convinced me that the difficulty is not due primarily to the depth of rainfall, but rather to the fact that the entire rainfall is immediately conveyed to the sewage system, thus producing an overload.

One aim of my invention is to impede the flow of rain water to the sewage system sufficiently so that the carrying off of the same may be spread over a greater period of time to reduce the maximum peak load on the system and render it more effective for carrying off the water.

Another aim of the invention is to provide a flow impeding structure of large drainage capacity so that even if, as might occur with cloud-bursts, the sewage system should overflow, the surplus water will be cared for by the drainage capacity of the flow impeding structure in a manner to prevent flooding of the streets.

In our northern cities great inconvenience and delay to foot and vehicular traffic is caused by the difficulty experienced in clearing the streets, sidewalks and bridges after a heavy snow storm. I have accordingly developed my invention particularly with the view to its applicability in solving this latter problem in a manner to avoid the main difficulties heretofore experienced with apparatus for melting and removing ice and snow from the roads, sidewalks, and so forth.

My invention accordingly may be said to relate to large capacity, slow draining surfacing construction for roads, pavements, bridges, ship decks and the like, adaptable for the melting of snow and ice and to aim generally to improve such construction. In addition it will be seen that some features of my invention will be applicable to the heating and draining of roofs upon which it is desired to prevent the accumulation of snow and ice to relieve weight or provide automobile storage space or the like.

Further individual aims of the invention are to provide a readily assembled road structure of this character; a structure which will be easily permanently assembled and which may be readily repaired; and a structure providing an even

surface and a sub-surface space to receive and conduct away the drainage from the surface and to provide for the ready supplying of heat to adapt the structure to melting snow and ice.

Other objects and advantages of my invention will be apparent from the following detailed description of an illustrative embodiment of the same.

Referring to the drawing forming a part of this application:

Fig. 1A is a plan view of a section of street and sidewalk according to one embodiment of my invention;

Fig. 1B is a sectional plan view of the same taken on line B—B of Fig. 2;

Fig. 2 is a transverse sectional view of the same, taken on line 2—2 of Fig. 1A;

Fig. 3 is a perspective view of one of the top surface carrying units shown assembled in Fig. 2;

Fig. 4 is a perspective view of a modified form of top surface carrying unit;

Fig. 5 illustrates a preferred form of heating pipe support for embodiment in my structural assembly; and

Fig. 6 is a section of a modified form of unit carrying a stone or wood block.

Referring to Fig. 2, the illustrative embodiment of my invention shown in the drawing comprises a sidewalk section 10, a road section 11, and a drain conduit 12, conveniently located under the sidewalk.

Bituminous or other resilient material is preferably used as the foundation material for my entire structure although it is clear that other compositions such as concrete could be utilized in this capacity in some instances.

Separating the sidewalk and road section is a curbing 13 made of suitable material to suit the exigencies of use and within this curbing a sidewalk foundation 14 is filled in above the drain conduit 12 to a height several inches below the top of the curbing 13.

This sidewalk foundation is constructed with a series of drain pipes 15 establishing communication between the top of the sidewalk foundation and the drain conduit 12. Top surface carrying units in the shape of inverted frusto-pyramidal members 16 are supported by the foundation material 14 with their lower ends embedded therein as shown, and with their upper edges abutting each other and the curbing 13, and level with said curbing. The edges of said blocks do not, however, continuously abut, but are provided with recessed edges, so that the discontinuous abutment provided thereby will result in the

provision of surfaces draining interstices 17 (Fig. 1A) therebetween, to conduct water from the top surface to the space 18 between the lower ends of the inverted frustro-pyramidal members, 5 from which space the water may flow by way of pipes 15 to the drainage conduit 12.

The frustro-pyramidal members 16, particularly in the smaller sizes thereof, are readily formed by stamping from sheet metal, although 10 I contemplate their construction from other materials or by casting. If the members are constructed hollow, as shown in the illustrative embodiment, it is necessary that a paving substance be provided therein. The units may be 15 filled with concrete, clay blocks or bituminous substance, but I prefer to form them with hollow base portions and I accordingly provide means for limiting the depth necessary to be filled with the surfacing material, which may take the form 20 of a sheet metal partition 19 having downturned edges so that it will take up an approximately level position in the unit, or a sheet metal or other partition as 20, (Fig. 2) which may be supported on lugs 21, struck out from, cast onto, or otherwise 25 provided at the side walls of the units 16.

Another modification can be made as shown in Fig. 6, wherein a pre-formed paving block 22 adapted to fit into the upper end of the frustro-pyramidal member with its top substantially 30 level with the upper edges thereof, is inserted therein, and self-sustained thereby. With this latter construction it is preferable to utilize a frustro-pyramidal member having drain openings 23 to prevent the accumulation of water 35 therein, as shown in Figs. 4 and 6, of which the inner top portions are flat, and in which the re-entrant drainage spaces are provided in a flange 25, as shown in Fig. 6, the details of such flange being more fully shown in Fig. 4.

40 The road section generally indicated by the numeral 11, must of course be constructed more substantially than the sidewalk section, because of the increased loads and wear to which it is subjected. The road foundation 14' is preferably 45 made of bituminous or other suitable road building material which may be laid over concrete as 14'', if desired, and is preferably slightly crowned as shown to provide for drainage toward the edges. The inverted frustro-pyramidal units 50 16' are set into the foundation material 14' at their bottoms and, due to the tenacity and resilience of the bituminous material, are firmly held in place even when subjected to the stresses of heavy traffic. These units may be progressively 55 set deeper toward the center of the road to maintain an uncrowned road surface, as shown, as crowning of the road surface is unnecessary with my system of drainage. The elimination of 60 side sliding of vehicles when the road is slippery. Another advantage of this progressively deeper setting is that the units are more firmly supported near the center of the street where they are subjected to greater stresses than at the edges. 65 The restriction of the sub-surface drainage space by this increasingly deeper setting is without detriment as there is less drainage to be cared for at the center of the street than at the edges because the drainage in the illustrative embodiment is toward the edges.

70 These frustro-pyramidal members 16' may take any form most suitable for the road surface construction desired, with or without false bottoms. Those shown embodied in Fig. 2 are 75 stamped out from sheet metal and provided with

struck up partition supports 21 to support the partition 20. The re-entrant portions 26, as best shown in Fig. 3, are produced by indentation during the stamping process, and each side of the square frustro-pyramidal member shown is provided with two such re-entrant portions, to enable the staggered assembly shown most clearly in Fig. 1A, while providing for the alignment of the re-entrant portions 26 of adjacent units to provide surface draining interstices, as best shown in said figure. This form of unit is particularly adapted to support paving of the bituminous, plastic, or hardening type indicated at 24 (Fig. 2) as the unhardened composition can be readily filled into the space above the partition in conformity with the re-entrant portions 26 which will assist in holding the material in place after it has set. On the other hand, if stone or wooden paving blocks as represented at 22, Fig. 6 are to be used I prefer to use a unit having substantially flat inner walls adjacent the top so that substantially flat faced blocks can be used. Such a unit is indicated at 16'' in Figs. 4 and 6. The unit 16'' may be cast with the recessed flange 25 or such flanged unit may be produced by known sheet metal working processes by turning the top edges outwardly and downwardly and stamping the re-entrant portions 26' only in the skirt portion thus formed. Furthermore if greater sub-surface drainage space is desired, I contemplate 105 forming the units in the shape more nearly like that of mushroom roof supporting columns, instead of with flat sides, and I do not intend to limit my invention to flat-sided by use of the term frustro-pyramidal. 110

To conduct the drainage from the sub-surface drainage space 27 of the road section 11 to the drainage conduit 12, I provide drain passages 28, through or below the curbing 13.

The construction shown in Fig. 2, due to the air 115 spaces within and between the several units 16', particularly when provided with an elastic or rubber block road surface element at 24, has the further advantage of muffling and deadening the noise of heavy traffic, and is therefore well adapted 120 for use in the larger cities.

The construction thus far described is suitable 125 for those cities troubled only by excessive rainfall, and in which the snow removal problem is not present.

The staggering of the frustro-pyramidal units produces to a considerable extent a retarding effect on the surface water draining off through spaces 27, thus lowering the peak demand on the sewage system. Moreover the large sub-surface 130 area 27 will provide overflow area to take care of excess water in case of a sudden cloudburst or the like.

To adapt my construction to the snow and ice removal problem of the northern cities it is merely 135 necessary to supply heat to the sub-surface areas. In connection with the preferred embodiment shown in the drawing I have indicated the preferable manner of so doing. To prevent freezing in the drainage conduit 12, I provide therein a 140 main 30 to conduct hot steam or other heated fluid. This main 30 is preferably uninsulated so that a portion of the heat of the fluid will be radiated into the conduit 12, and is supported by pipe hangers 30' as shown. If steam is used the 145 main may be perforated, if desired, to allow the desired amount of steam to escape into the drainage conduit 12.

This is particularly advantageous, in connection with the embodiment shown, where snowfall 150

is heavy, as the expanding steam will flow in a steady current upwardly through the pipes 15 to cause more rapid melting of the snow and ice on the sidewalk than would be obtained by depending solely on the natural distribution of radiated heat from the main 30 by conduction or convection.

For heating the road sub-surface in the embodiment shown, I provide laterals 31 extending from the main 30, through certain of the drain passages 28. It is well known, of course, that the greatest accumulation of snow and ice occurs in the street adjacent the curbing. I have therefore conceived that the greatest degree of heat should be applied adjacent the curbing. In addition, in combination with a crowned sub-surface, it is desirable to stagger the units in such a manner that tortuous drain passages are provided from the center toward the edges of the street to retard the flow-off, while it is not essential that the passages be staggered longitudinally of the street, as other means provided by my invention serve to retard flow-off longitudinally of the street when this is desirable, as when the street runs up or down hill.

With all these considerations in mind, I accordingly arrange my units 16' in rows C. D. E. etc. paralleling the curbing, alternate rows being staggered with respect to each other as clearly shown in the drawing. Each lateral 31, after passing under the curbing, is turned parallel thereto and run longitudinally of the road in the straight, longitudinal space between the first row (row C.) and the curbing, for a suitable distance which is not so great that the radiation therein will unduly diminish the heat available in the heated fluid. Thus the greatest degree of heat is applied adjacent the curbing.

The lateral is then turned as indicated at 32 and passed between adjacent units of the first row of units (row C.) to the adjacent longitudinal space through which it is run parallel to the curb for a suitable distance, after which, as indicated at 33, it is passed through the next row of units (row D.) and run parallel to the curbing in the next longitudinal space, and so on. In the preferred embodiment I have shown the lateral 31, 32, 33 as running back and forth in a zig-zag manner, which will thus serve to heat a transverse section of the roadway as a single unit. Each lateral 31 may be provided with a cut-off valve, as shown at 35, so that steam may be cut off in sections at which the snow and ice has been entirely melted and drained away, to conserve steam, while continuing to heat adjacent sections where a greater accumulation of snow, as a drift, must be removed. These valves 35 may be conveniently operated by a removable long-stemmed handle fittable to a valve stem 36, which may conveniently pass upwardly through one of the drain pipes 15, adjacent the curb. The unit or units adjacent the stem 36 should be recessed as indicated at 37, Fig. 2, to provide for ready access to the stem 36.

In order that the valves may be more readily located by the operator, I prefer to run the laterals alternately in opposite directions, as indicated in Fig. 1B, so that two valves will lie adjacent each other and be more readily located, because of the presence of two adjacent recesses 37 at the surface.

In order to elevate the laterals 31, 32, 33 etc., to prevent as far as possible the loss of heat through absorption thereof by the water draining off through the spaces 27, and also in order to

baffle the longitudinal flow-off of water when the road runs down hill, I provide combined pipe supports and baffle members 40, clearly shown assembled in my construction in Figs. 1 and 2, and of which an enlarged section of a preferred embodiment is shown in Fig. 5. These supports and baffles are cheaply produced in a very good form from strips of sheet metal bent up to provide an upwardly projecting baffle vane 41, having a portion clipped out of its uppermost edge to form a pipe receiving recess 42. These formed strips are incorporated in the structure so that they lie along the longitudinal spaces of the sub-surface area 27, between the curbing and the row of units C, and between each pair of adjacent rows of units C—D, D—E, etc. The upwardly projecting baffle members 41 not only support the heating pipes above the normal flow-off level of the water to prevent loss of heat by dissipation through contact with the water, but also act as baffles, when the road runs down hill, to impede the flow of water along the longitudinal spaces of the sub-surface area 27, and deflect it laterally into the transverse, staggered, spaces thereof, thus to reduce the peak load upon those portions of the sewage system subject to the greatest flow-off.

Thus these baffles serve a useful purpose in taking care of excessive rainfall or the like, when heated fluid is not passing through the piping, and serve a double purpose when the pipes are conducting heated fluid for snow and ice removal.

If all the lateral supporting strips 40 are of the same height, the laterals will be most elevated adjacent the center of the road, which will be desirable in some instances.

On the other hand I contemplate using strips of progressively decreasing height to counteract the effect of a crowned sub-surface, to lower that end of the lateral 31 terminating at the center of the road, so that waste steam and condensate will be ejected at this point where it will be serviceable in rapidly clearing the center of the road for traffic.

For most rapid thawing with steam as the heated fluid I prefer to perforate the laterals so that the expanding steam will pass into contact with, and upwardly between, the walls of the units 16' to effect a more rapid removal of the snow and ice, as detailed above in connection with the clearing of the sidewalk. The supply of heat may be roughly proportioned to the quantity of melting expected to be necessary, by varying the number or size of perforations, if desired.

I of course contemplate the provision of drain openings at the lowermost portions of the laterals, and of the main (the location of which portions will vary with the inclination of the street) to prevent the accumulation of condensate or water in the system which might cause freezing and bursting of the pipes if provision were not made for the draining off thereof.

I have described, for purposes of illustration only, certain preferred embodiments of the various features of my invention, but by so doing I do not intend to limit my invention by the specific disclosures set forth.

What I claim is:

1. A self draining surface construction for pavements comprising a sub-surface, a plurality of inverted frusto-pyramidal members arranged with their top portions in abutting relation and with their bottom portions set into said sub-surface and defining open drainage spaces therebe-

tween above said sub-surface, each of said members being adapted to support a section of paving surface and having a plurality of interstices extending downwardly from the surface of the paving between their abutting edges and communicating with the drainage spaces.

10 2. A self draining surface construction for flat pavements comprising a crowned sub-surface, a plurality of inverted frustro-pyramidal members arranged with their top portions in level abutting relation and with their bottom portions set into said sub-surface and defining drainage spaces therebetween, each of said members being adapted to support a section of paving surface, and having a plurality of interstices extending downwardly from the surface of the paving between their abutting edges and communicating with the drainage spaces.

20 3. A self draining surface construction for heated pavements comprising a crowned sub-surface, a plurality of inverted frustro-pyramidal members arranged with their top portions in level abutting relation and with their bottom portions set into said sub-surface and defining drainage spaces therebetween, each of said members being adapted to support a section of paving surface, a plurality of interstices extending downwardly from the surface of the paving and communicating with the drainage spaces, and means for supplying heat to said drainage spaces.

30 4. A self draining surface construction for a heated pavement comprising a crowned sub-surface, a plurality of inverted frustro-pyramidal members, arranged with their top portions in level abutting relation and with their bottom portions set into said sub-surface, and defining drainage spaces therebetween, each of said members being adapted to support a section of paving surface, said members being disposed to provide a plurality of interstices extending downwardly from the surface of the paving and communicating with the drainage spaces beneath, and means for supplying heat to said drainage spaces below said surface in such quantity to the different parts thereof respectively as is roughly proportionate to the relative quantity of melting expected to be necessary at said respective parts.

50 5. A self draining surface construction for draining away surface water and adapted for the melting of snow and ice, comprising a crowned sub-surface, a plurality of inverted frustro-pyramidal members, arranged with their top portions in level abutting relation and with their bottom portions set into said sub-surface, and defining drainage spaces therebetween, each of said members being adapted to support a section of paving surface, a plurality of interstices extending downwardly from the surface of the paving and communicating with the drainage spaces and means comprising pipes for supplying heat to said drainage spaces for melting snow and ice on said paving surface.

60 6. A self draining surface construction for draining away surface water, comprising a crowned sub-surface, a plurality of inverted frustro-pyramidal members, arranged with their top portions in level abutting relation and with their bottom portions set into said sub-surface, and defining drainage spaces therebetween, each of said members being adapted to support a section of paving surface, a plurality of interstices extending downwardly from the surface of the paving and communicating with the drainage spaces, and means comprising pipes supported above the normal level of flow of water produced

by the melting of ice and snow, for supplying heat to said drainage spaces for melting snow and ice on said paving surface.

7. A self draining pavement construction comprising a crowned sub-surface, a plurality of inverted frustro-pyramidal members, arranged with their top portions in level abutting relation and with their bottom portions set into said sub-surface, and defining drainage spaces therebetween, each of said members being adapted to support a section of paving surface, a plurality of interstices extending downwardly from the surface of the paving and communicating with the drainage spaces, and means comprising pipes supported above the normal water level by combined baffle and pipe supporting members for supplying heat to said drainage spaces for melting snow and ice on said paving surface.

8. A self draining pavement construction comprising a crowned sub-surface, a plurality of inverted frustro-pyramidal members, arranged with their top portions in level abutting relation and with their bottom portions set into said sub-surface, and defining drainage spaces therebetween each of said members being adapted to support a section of paving surface, a plurality of interstices extending downwardly from the surface of the paving and communicating with the drainage spaces, and means comprising pipes supported above the normal water level by combined baffle and pipe supporting members comprised of strips having upstanding baffle portions provided with seats for said pipes for supplying heat to said drainage spaces for melting snow and ice on said paving surface.

9. In a heated road construction, a sub-surface drainage space communicating with the road surface for receiving drainage water therefrom and heating pipes supported therein above the normal water level by combined pipe supports and baffles.

10. In a heated road construction, a sub-surface drainage space communicating with the road surface for receiving drainage water therefrom and heating pipes supported therein above the normal water level by combined pipe supports and baffles comprising a strip of material sufficiently rigid to sustain the weight of the pipes having baffle members upwardly projecting therefrom and formed at their top edges to receive and support said pipes.

11. A road construction comprised of discontinuously abutting inverted frustro-pyramidal members supported by a sub-surface and providing a sub-surface drainage space and interstices communicating from the surface to said sub-surface drainage space, said members being arranged in alining rows in one direction, the individual members of said rows being staggered in the other direction.

12. A road construction comprised of discontinuously abutting inverted frustro-pyramidal members supported by a sub-surface and providing a sub-surface drainage space and interstices communicating from the surface to said sub-surface drainage space, said members being arranged in rows in one direction, the individual members of said rows being staggered in the other direction, and baffles arranged upstandingly in the spaces between said rows so that flow-off is impeded in both directions.

13. A road construction comprised of discontinuously abutting inverted frustro-pyramidal members supported by a sub-surface and providing a sub-surface drainage space and interstices communicating from the surface to said sub-surface drainage space, said members being arranged

- in rows in one direction, the individual members of said rows being staggered in the other direction, baffles arranged upstandingly in the spaces between said rows, so that flow-off is impeded in both directions, and heating pipes supported by the tops of said baffles. 5
14. A road construction unit comprising an inverted frustro-pyramidal member provided at its upper wider end with indented drain portions. 10
15. A road construction unit comprising an inverted frustro-pyramidal member provided at its upper wider end with a flange having indented drain portions. 15
16. A road construction unit comprising an inverted hollow frustro-pyramidal member provided at its upper wider end with a flange having indented drain portions. 20
17. A road construction unit comprising a hollow frustro-pyramidal member provided at its wider end with a flange having indented portions, means for limiting the depth available for filling with wear surfacing material, and wear surfacing material filling said member to said limited depth. 25
18. A road construction unit comprising a hollow frustro-pyramidal member provided at its wider end with a flange having indented portions, means for limiting the depth available for filling with wear surfacing material comprising a partition, and wear surfacing material filling said member to said limited depth. 30
19. A road construction unit comprising a hollow frustro-pyramidal member provided at its wider end with flange having indented portions, means for limiting the depth available for filling with wear surfacing material comprising a partition or false bottom supported therein by means provided for holding the same substantially level, and wear surfacing material filling said member to said limited depth. 35
20. A road construction unit comprising a hollow frustro-pyramidal member provided at its wider end with a flange having indented portions, means for limiting the depth available for filling with wear surfacing material comprising a partition or false bottom supported therein by means carried by said member for holding the same substantially level, and wear surfacing material filling said member to said limited depth. 40
21. A self draining road comprising a substantially even or flat road surface carried by inverted frustro-pyramidal members supported at intervals upon a crowned sub-surface and having interstices communicating from the road surface to the space therebelow between the members, to obtain a quick run-off as by crown draining while maintaining a flat road surface. 45
22. A self draining road adapted for snow and ice removal comprising a substantially even or flat road surface supported at intervals upon a crowned sub-surface and having interstices communicating from the road surface to the space therebelow between the supports, to obtain a quick run-off as by crown draining while maintaining a flat road surface, and pipes for supplying heat supported in said space in spaced relation to said crowned surface and above the normal level of flow thereover of water resulting from the melting of snow and ice. 50
23. A self draining surface construction for pavements comprising a sub-surface, a plurality of inverted frustro-pyramidal members, arranged with their top portions in abutting relation and with their bottom portions set into said sub-surface and defining drainage spaces therebetween, each of said members being adapted to support a section of paving surface and having drainage indentations at its top portion. 55
24. A self draining surface construction for pavements comprising a sub-surface, a plurality of inverted frustro-pyramidal members arranged with their top portions in abutting relation and with their bottom portions set into said sub-surface and defining drainage spaces therebetween, each of said members being recessed at the top to receive and support a section of paving surface and having a plurality of interstices extending downwardly from the surface of the paving between their abutting edges and communicating with the drainage spaces. 60
25. A road construction comprised of abutting inverted frustro-pyramidal members having discontinuous abutting edges supported by a sub-surface and providing a sub-surface drainage space and interstices communicating from the surface to said sub-surface drainage space. 65
26. A road construction comprising a plurality of abutting, inverted, open-based, frustro-pyramidal members provided at their wider, open ends with indented portions rendering the abutment of said members discontinuous, and road surfacing material carried within the confines of the open bases of said members. 70
27. A road construction comprising inverted hollow frustro-pyramidal members provided at their wider ends with indented drain portions. 75
28. A road construction unit comprising a hollow frustro-pyramidal member provided at its wider end with indented portions, means for limiting the depth available for filling with wear surfacing material, and wear surfacing material filling said member to said limited depth. 80
